DESIGN FOR A SHIRRED FABRIC

Charles Sturzlinger, New York, N. Y.

Application September 13, 1940, Serial No. 95,015

Term of patent 14 years

To all whom it may concern:

Be it known that I, Charles Sturzlinger, a citizen of the United States, residing at New York, in the county of New York and State of New York, have invented a new, original, and ornamental Design for a Shirred Fabric, of which the following is a specification, reference being had to the accompanying drawing, forming a part thereof, wherein:

Figure 1 is a plan view of a portion of shirred fabric showing my new design,

Figure 2 is a section taken on the line 2—2 of Figure 1,

My design for a shirred fabric is characterized by shirred areas of the specific type as illustrated at alternate distances from each other with plain fabric portions between each of the shirred areas.

I claim:

The ornamental design for a shirred fabric, substantially as shown and described.

CHARLES STURZLINGER.
